UNITED STATES PATENT OFFICE.

ALBERT LOUIS COLMANT, OF CHATENAY, FRANCE.

EXPLOSIVE-ENGINE.

1,101,408.

Specification of Letters Patent. Patented June 23, 1914.

Application filed January 20, 1913. Serial No. 743,217.

To all whom it may concern:

Be it known that I, ALBERT LOUIS COLMANT, a citizen of the French Republic, and resident of Chatenay, France, have invented certain new and useful Improvements Relating to Explosive-Engines, of which the following is a specification.

The present invention relates to an internal combustion engine of great simplicity and high efficiency.

The invention also comprehends improvements in the specific construction and arrangement of parts which will be herein-after described and particularly pointed out in the claims.

The accompanying drawing illustrates a vertical section of an engine constructed in accordance with my invention.

The numeral 8 indicates a cylinder, in 20 the top of which, at B, a spark plug is mounted. The cylinder is supported on a plate 8^a, and to the under side of this plate is attached a crank case 7. Extending upwardly in the cylinder, and formed integral 25 with plate 8^a, is a smaller cylinder 6, spaced from the inner walls of cylinder 8, closed at its top, save for a small opening 8^x, and open at the bottom. Operating in the cylinder 8, is a hollow piston, on the top of which 30 is a deflector 2, and depending centrally from the under side of the piston is a rod 9^a, pivotally connected at its lower end to a connecting rod 4, which in turn is connected to a crank shaft 5. The depending rod 9^a passes through the opening 8^x, and near its 35 lower end it is provided with a cross head 3, which operates in the cylinder 6.

The cylinder 8 is formed in one side with an inlet port A, and in the opposite wall 40 with an exhaust port E, these two ports being substantially in alinement. When the piston is in its lowermost position the ports A and E are open. The port A communicates, by means of a duct A', with a gas port 45 10, formed in the lower end of cylinder 8, just over plate 8^a.

A pipe 11 communicates with the cylinder 8 at 12, between ports A and 10. In this pipe is formed a chamber 11^a, in which a 50 ball valve 13 operates. A spring 13^a acting on valve 13 serves to normally close the inlet to the chamber. Communicating with the top of the chamber 11^a, is a pipe 15, and surrounding the latter is a screen 14.

Below ports A and E, and above the level 55 of the pipe 11, are air inlet openings o,

which are closed by the piston, except when the latter is at the limit of its upward movement.

In operation, (assume the piston is in the 60 position shown in the drawing) when said piston rises, it creates a partial vacuum in the cylinder, and in the duct A'. As soon as the open end 12 of pipe 11, is uncovered, and a charge is drawn into the cylinder, the 65 partial vacuum unseats valve 13, allows the fuel to pass, and at the same time, a charge of air from pipe 14 is drawn in. The mixture, when introduced in the cylinder, in an atomized condition, contacts with the hot 70 walls of said cylinder and is immediately converted into gas. In the continued upward movement of the piston, the air inlet ports are uncovered, and the partial vacuum is destroyed, hence the ball valve 75 13, immediately closes. Upon the descent of the piston the charge below same is slightly compressed, and immediately port A is uncovered, the compressed charge is forced through ports 10 and A', and into the cylinder above the piston. Now, upon the next 80 ascending stroke of the piston, the charge above the piston will be compressed and fired, as is usual in engines of this type:

What I claim is:

1. An explosive engine comprising a cylinder, the cylinder having an upper port and a lower port and an exhaust port adjacent said upper port, a duct connecting the upper and lower ports, a fuel supply 90 pipe communicating with the cylinder between the upper and lower ports, a check valve in the feed pipe which is normally closed, the fuel supply pipe having an opening for the admission of a supply of air to 95 mix with the fuel passing through said pipe, said cylinder having an air inlet opening below the plane of the exhaust and upper ports, a hollow piston operating in the cylinder, a crank shaft, and connections between the crank shaft and piston, whereby when the piston is in its lowest position the upper port and the exhaust port are open and the fuel pipe and air inlet opening are closed and when said piston is raised said 100 upper and exhaust ports will be closed and a vacuum formed below the cylinder and a charge of fuel and air introduced into the cylinder and an additional supply of air will be subsequently admitted through the 110 air inlet ports.

2. An explosive engine comprising a cas-

ing, a cylinder mounted on the casing, a smaller cylinder extending from the casing into the first mentioned cylinder, a hollow piston operating in the first mentioned cylinder, a rod extending from the piston and through the smaller cylinder, a cross head on the rod, said cross head operating in the smaller cylinder, a crank shaft mounted in the casing, a connecting rod between the 5 crank shaft and the rod, communicating ports which form communication with the cylinder above and below the piston when the latter is in its lowest position, a fuel supply pipe communicating with the cylinder between the two aforesaid communicating ports, a check valve in the pipe to normally close the latter, the said pipe having an air inlet opening between the valve and the cylinder, and the cylinder having an 10 air inlet above the plane of the fuel supply pipe, whereby when the piston is elevated a partial vacuum is formed and a supply of fuel and air is drawn into the cylinder and subsequently upon the further upward 15 movement of the piston, a further supply of air is admitted and when said piston descends, the charge is forced through the aforesaid two communicating ports and into the cylinder above the piston.

20 3. A two stroke explosive engine comprising a casing, a cylinder mounted on the casing, the cylinder having two communicating ports which communicate with the

cylinder, the cylinder having an exhaust port, the upper one of the communicating ports and the exhaust port being uncovered by the piston when the latter is in its lowermost position, the cylinder having a plurality of air inlet ports which are uncovered when the piston is at its uppermost position, 25 a sparking plug on top of said cylinder, a piston moving to and fro within said cylinder, a deflector on top of said piston, a piston rod, a cross head on said piston rod, a crank shaft, a connecting rod between said 30 crank shaft and said cross head, a bottom plate on said casing, a central cylinder mounted on said bottom plate to form a guide for the cross head, an oil and air inlet tube opening into said cylinder at a level corresponding to the middle of the piston when the latter is in its lowermost position, a chamber provided in said tube, a ball in said 35 chamber for closing the oil inlet, a spring for maintaining said ball in closed position, 40 said chamber having an air inlet opening, a wire gauze covering said opening whereby oil will enter said tube when a vacuum is produced below the piston during its upward motion.

In testimony whereof I have hereunto set my hand in presence of two witnesses.

ALBERT LOUIS COLMANT.
